D. C. DAVIS.
MECHANICAL CONVERTER,
APPLICATION FILED JULY 3, 1916.

1,404,838.

Patented Jan. 31, 1922.

UNITED STATES PATENT OFFICE.

DAVID C. DAVIS, OF WILKINSBURG, PENNSYLVANIA, ASSIGNOR TO WESTINGHOUSE ELECTRIC AND MANUFACTURING COMPANY, A CORPORATION OF PENNSYLVANIA.

MECHANICAL CONVERTER.

1,404,838.

Specification of Letters Patent. Patented Jan. 31, 1922.

Application filed July 3, 1916. Serial No. 107,376.

To all whom it may concern:

Be it known that I, DAVID C. DAVIS, a citizen of the United States, and a resident of Wilkinsburg, in the county of Allegheny and State of Pennsylvania, have invented a new and useful Improvement in Mechanical Converters, of which the following is a specification.

My invention relates to mechanical converters for use in connection with electrical circuits and more particularly to converters of the type employed in the rectification of alternating currents and commonly designated as rectifiers. One of the salient features of my invention is the use of a series of spaced globules of adjustable length for circuit-controlling purposes, said globules being formed of a conducting liquid.

My invention has for one of its objects to provide apparatus of the character designated which shall be extremely flexible in adjustment and which shall readily lend itself to the rectification of large amounts of energy, whether of high voltage or of large current.

Another object of my invention is to provide an automatic controlling device for apparatus of the character designated whereby sparking may be reduced and, at all times, be maintained at a minimum. Other objects of my invention will hereinafter more fully appear.

In the accompanying drawing, Fig. 1 is a diagrammatic view of a rectifying system embodying a preferred form of my apparatus, partially in section and partially in elevation; Fig. 2 is an enlarged sectional view of a pair of contact members employed in the system of Fig. 1; and Fig. 3 is a wave diagram to be used in connection with the explanation of the method of operation.

Referring to Fig. 1 for a more detailed understanding of my invention, I show a source of alternating-current, such, for example, as a transformer 5. The terminals of the secondary winding 6 of the transformer 5 are connected, in any desired manner, to a plurality of pairs of electrodes 7-7 and 8-8 mounted respectively on the inner surfaces of two tubes 9 and 10, composed preferably of refractory insulating material, such, for example, as quartz or refractory glass. The electrodes 7-7 and 8-8 are composed of a fairly refractory material, such, for example, as iron, copper or tung-

sten and each of them is preferably provided with an extension or tip 11 of refractory conducting material, such, for example, as carbon, at its upper end, as clearly indicated in Fig. 2, the purpose of which will herein-after more fully appear. The interior of the tube 10 communicates with a supply tube 12 through a suitable slip joint indicated at 13, and, in like manner, the interiors of the tubes 10 and 9 are in connection through a suitable sleeve or thimble 14 having a sliding engagement with one or both of said tubes, the tubes 9, 10 and 14 forming a rectifying unit 140. Similarly, the interior of the tube 9 is in connection with an exhaust or outflow tube 15 through a slip joint indicated at 16. The tube 10 may be raised and lowered throughout the range permitted by said slip joints by any suitable means, such, for example, as a handle 17 and, in like manner, the tube 9 may be raised and lowered by a handle or other operating mechanism 18. The tubes 9 and 10, together with their attendant electrodes and connecting tubes, are designed to present a smooth and uniform interior surface, care being taken to avoid protuberances of any nature which would serve to produce eddies or other disturbances in a liquid flowing therethrough.

A closed tank or receptacle 19 of considerable size is partially filled with a conducting liquid, such, for example, as mercury, as indicated at 20, and the remainder thereof is substantially filled by an insulating fluid, such, for example, as oil, as indicated at 21. Two outflow tubes 22 and 23 are attached to the tank 19, the inlet port to the tube 22 being so disposed that insulating fluid flows thereto at all times, the inlet port to the tube 23 being so disposed that conducting fluid flows thereto at all times. The tubes 22 and 23 terminate in valve chambers 24 and 25, exit from which is controlled by two slide valves 26 and 27 which are oscillated by a synchronous motor 28 operated from the source 5. Each of the slide valves 26 and 27 is provided with a single port therethrough, said ports being designated as 29 and 30. Two tubes 31 and 32 terminate above the valve 26, and, in like manner, two tubes 33 and 34 terminate above the valve 27. The tubes 31 and 34 merge to form the supply tube 12 communicating with the interiors of the tubes 9 and 10, and the tubes 32 and 33

merge into a by-pass tube 35 provided with a throttling or regulating valve 36, as indicated. The outflow tube 15, communicating with the tube 9, merges with said by-pass tube 35, and said tubes jointly communicate with the intake of a device 37, combining the functions of a circulating pump and a centrifuge. Said device 37 is driven by any suitable means, such, for example, as a motor 38 and may, if desired, comprise two separate machines of the character indicated, mounted upon a single shaft. The outflow from the device 37 preferably comprises a double tube 39-40, the centrifuge action tending to separate the oil from the mercury, the mercury, because of its greater specific gravity, being thrown out into the tube 39 and thence flowing to the lower portion of the tank 19, whereas the oil flows through the tube 40 to the upper portion of said tank.

Having thus described the arrangement of apparatus embodying my invention, the operation is as follows. In the oscillation of the valves 26 and 27, the port 29 is, for an instant, in communication with the tube 31, and the port 30 is, at the same time, in communication with the tube 33. Under these conditions, with the pump 37 operating to force a circulation of both fluids through the system, a substantial amount of mercury is admitted from the chamber 24 to the tube 31, causing a like amount of mercury or other conducting fluid to pass into the lower end of the tube 10 and, at the same time, a similar amount of insulating fluid is admitted to the tube 33 through the port 30 and thence returns to the pump 37 via the by-pass tube 35. The ports 29 and 30 now move to the right, passing under partitions or septa 41 and 42 which separate the tubes 31 and 32 and 33 and 34, respectively, whereupon the flow of conducting fluid is diverted from the tube 31 to the tube 32 and the by-pass, and the flow of insulating fluid is diverted from the tube 33 to the tube 34, and thence to the supply tube 12 and the rectifying tubes 9 and 10. As the result of the above-described action, the motor 28 driving the valves 26 and 27 in synchronism with the supply, a globule of conducting liquid and a globule of insulating liquid are forced upwardly through the tubes 9 and 10 for each half cycle of the supply, said conducting globules being indicated at 43-43 and said insulating globules at 44-44. The spacing of the conducting globules from each other and the spacing of the pairs of electrodes in the tubes 9 and 10 is such that, at a given instant, a distinct conducting globule is just making contact with each pair of electrodes in the tube 10 and, at the same instant, a distinct conducting globule is just breaking contact with each

pair of electrodes in the tube 9. The adjustment is such that the circuit is thus closed at each pair of electrodes 8-8 at the instant when current flow from or to the lower end of the secondary winding 6 is desired and at which it is therefore desired that current flow from or to the upper end of said secondary winding 6 cease.

As indicated, there are four pairs of electrodes 8-8 in the tube 10, and the two upper pairs and the two lower pairs are connected in parallel relation, respectively. The two parallel combinations thus formed are connected in series with each other between the lower end of the secondary winding 6 and one terminal of a suitable load 45, such, for example, as a storage battery. The four pairs of electrodes 7-7 in the tube 9 are similarly connected between the upper terminal of the secondary winding 6 and the same pole of the battery 45. The remaining pole of said load battery is connected to the mid-point of the secondary winding 6, as is usual in rectifying circuits. By the system of connections thus outlined, it will be noted that the circuit is simultaneously closed at all four of the pairs of electrodes 8-8 and that said electrodes are arranged in two parallel groups, whereby the rectification of a large amount of current is possible, and that said groups are arranged in series with each other, whereby a high voltage may be rectified without difficulty, because of the subdivision thereof.

A half cycle later, the above conditions of operation are reversed, conducting globules are just coming into contact with each pair of electrodes 7-7 in the tube 9 and are just breaking contact with each pair of electrodes 8-8 in the tube 10, thus permitting current flow of great magnitude and of high voltage from the upper terminal of the secondary winding 6 to the load 45. Obviously, the rectifying action just described is capable of indefinite expansion in that three or more pairs of electrodes arranged to coat simultaneously with three or more successive operating globules may be combined in parallel with each other for the rectification of current of any desired magnitude and, furthermore, any desired number of pairs of electrodes may be connected in series therewith to coat simultaneously with different conducting globules for the rectification of current of any desired voltage. It should further be particularly noted that, by my invention, a conducting globule, after operating to assist in the rectification of several alternating-current waves of one polarity, passes over to the other side of the system and there assists in the rectification of a like number of alternating-current waves of the opposite polarity.

The object of the refractory tips 11-11 on

the respective electrodes is to divert and suppress such sparks as may occur at the instant of breaking circuit because of the fact that the electromotive force of the supply wave at 5 said instant is not equal and opposite to the back electromotive force of the load.

It is obvious that the valve mechanism should be so adjusted that the insulating globules are much longer than the conducting globules, even when operating on a pure-resistance load, wherewith the circuit for waves of each polarity is closed for an entire half cycle, as the circuit is closed from the instant the upper portion of a globule 10 makes contact with the lower portion of a pair of electrodes until the time when the lower portion of the globule leaves the upper portion of a pair of electrodes. This dissymmetry in the relative size of the conducting and insulating globules is even greater 15 when operating on a load having a back electromotive force, as, under these conditions it is desirable to maintain the circuit closed only during a portion of the central 20 zone of each alternating-current wave.

The purpose of the by-pass tube 35, together with the valve outlet tubes 32 and 33 is to eliminate all stoppage of fluid flow as, 25 at the velocity with which the mechanism must operate on commercial frequencies, severe liquid hammer would ensue if it were attempted to entirely stop the liquid flow with each half cycle. The purpose of the throttling or regulating valve 36 is to adjust the frictional hydrostatic head in the by-pass tube 35 to an amount substantially 30 equal to that encountered in the rectifying tubes and in the return tube 15, thus permitting a symmetrical distribution of the 35 fluids throughout the system. As further aiding proper circulation in the system, the tube 22 should be somewhat restricted in cross section with respect to the fluid flow therethrough, as compared with the tube 40 23, thus compensating for the greater tendency of the light insulating fluid to circulate through the system under the constant propelling force of the device 37.

It is desirable, in my rectifying apparatus, in common with all other types of rectifiers, to reduce sparking to a minimum. The principal cause of sparking is to attempt to break the rectifying circuit when 45 current is flowing therein because of unbalanced voltage conditions. If the instant of break, when charging a battery, for example, can be adjusted to the time when the voltage of the alternating-current wave is balanced by the back electromotive force of 50 the battery no sparking will ensue. By reference to Fig. 3 wherein 46 represents a voltage wave of the supply, 47-47 represents the battery voltage at the beginning of 55 charge and 48-48 represents the battery voltage at the end of charge, it is noted that

the proper time for closing the rectified circuit grows later as the charge progresses, and the proper time for breaking said circuit grows earlier under like conditions. There are other contributing causes to 70 sparking, such, for example, as alterations in the shape and magnitude of the supply-voltage waves. It is accordingly desirable to provide auxiliary apparatus that shall respond to sparking and shall so adjust the 75 above-described apparatus as to eliminate said sparking. Said adjustment should be in the nature of increasing or decreasing the length of the conducting globules in the tubes 9 and 10 while producing a supplementary alteration in the length of the insulating globules, one criterion of successful operation being that the sum of the 80 lengths of a conducting and of an insulating globule shall be, at all times, substantially equal to the distance between the centers of two successive pairs of electrodes. This adjustment should be in addition to the initial vertical adjustment of the tubes 85 9 and 10 by means of the handles 17 and 18, whereby the center of a conducting globule is brought opposite the center of a pair of electrodes at the instant of maximum voltage in a half cycle.

I provide the above-described automatic 95 adjustment of the length of the conducting globules by means of two resistance coils 49 and 50 mounted adjacent to a pair of electrodes, together with associated apparatus. The coils 49 and 50 are closely wrapped 100 around the upper portion of a pair of electrodes, as indicated in Fig. 2, but the coil 50 is preferably further removed from the tube than is the coil 49 and should, in addition, have a greater heat capacity. The 105 coils 49 and 50 are composed of some such material as iron which has a very perceptible change in resistance, with a change in temperature. The coil 49 is inserted in one side of a Wheatstone bridge 51 while the coil 50 is inserted in the corresponding side of a Wheatstone bridge 52. The upper and lower corners of the bridges 51 and 52 are energized from a suitable current source 53 and the remaining sides thereof contain resistance members, as shown, whereby, at 110 normal temperatures, the side terminals of said bridges are maintained in potential equilibrium. The two side terminals of the bridge 51 are connected together through the operating winding of a relay 54 and a "down" interlock on a relay 55. The contact members of the switch 54, when closed, energize a motor 56 which is adapted, through suitable gearing, to move the septums 41 and 42 slightly to the left, thus shortening the 115 conducting globules and correspondingly lengthening the insulating globules in the tubes 9 and 10, without disturbing the location of the centers of the conducting glob- 120 125 130

ules with respect to the centers of the electrodes at the instant of maximum voltage in each supply wave. The side terminals of the bridge 52 are connected together through 5 the operating winding of the relay 55, and said relay, when operated, serves to de-energize the relay 54 and to close a circuit operating the motor 56 in the reverse direction and moving the septums 41 and 42 to the 10 right, thus lengthening the conducting globules and correspondingly shortening the insulating globules.

The operation of said automatic regulating device is as follows. Let it be assumed 15 that there has developed such a mis-timing of the point of break that sparking takes place at the pair of electrodes encompassed by the windings 49 and 50. Both of said windings are affected by the heat of said 20 sparking but the winding 49, because of its greater proximity and smaller heat capacity, is affected much more rapidly and serves to first unbalance the bridge 51 to such a degree as to operate the relay 54, causing the 25 motor 56 to move the septums 41 and 42 to the left, shortening the conducting globules within the tubes 9 and 10, as desired. If, for any reason, however, the undesired sparking 30 arises, not from too late but from too early a break, said operation of the bridge 51 serves but to increase the same. Under these conditions, the coil 50 is soon affected to such an extent as to unbalance the bridge 52, operating the relay 55, first to de-energize the 35 relay 54 and then to drive the motor 56 in the opposite direction, moving the septums 41 and 42 to the right until sparking disappears.

Under either condition of operation, the 40 cessation of sparking causes the coils 49 and 50 to reassume their cold resistance, balancing the bridges 51 and 52, de-energizing whichever relay 54 or 55 is closed and stopping the motor 56.

If an automatic regulating device be desired which shall even more effectively protect the system from sparking, I may subdivide the windings 49 and 50, placing a portion of each thereof in operative proximity 45 to each of the pairs of rectifying electrodes, ensuring a corrective action whenever sparking occurs at any pair of electrodes but, for clearness of illustration, I have shown said resistance windings as applied to only one 50 pair of electrodes.

If the tank 19 be of sufficient capacity, I 55 may do away entirely with the centrifuge action in the device 37, depending entirely upon natural settlement within the tank 19 to separate the conducting and insulating fluids.

I have shown the spark-responsive or thermo-responsive regulating apparatus as applied to a rectifier but it is obvious that similar apparatus may be applied to obviate

sparking in all types of electrical apparatus, as, for example, in dynamo-electric machinery of the commutator type, etc.

While I have shown my invention in several forms, it will be obvious to those skilled 70 in the art that it is susceptible of various minor changes and modifications without departing from the spirit thereof and I desire, therefore, that only such limitations shall be placed thereupon as are imposed 75 by the prior art or as fall within the scope of the appended claims.

I claim as my invention:

1. A circuit-controlling aggregate comprising a pair of spaced electrodes, means 80 for producing a succession of alternate conducting and insulating liquid bodies passing therebetween and making contact therewith, and means for changing the relative lengths of said conducting and insulating liquid 85 bodies while maintaining their velocity substantially constant.

2. The combination with a tube composed of insulating material, of a pair of electrodes mounted on the inner surface thereof, an electric circuit connected to said electrodes, means for forcing therethrough a stream of distinct conducting liquid globules of sufficient size to simultaneously make contact with both of said electrodes, and means 95 for changing the lengths of said globules while maintaining their velocity substantially constant.

3. The combination with a tube composed of insulating material, of a pair of electrodes mounted on the inner surface thereof, an electric circuit connected to said electrodes, means for forcing a stream of alternate conducting and insulating globules through said tube, said means operating to 100 make said conducting globules of sufficient size to simultaneously make contact with each of said electrodes, and means for changing the relative lengths of said conducting and insulating globules while maintaining their velocity substantially constant. 105

4. The combination with a tube of insulating material, of a pair of spaced electrodes mounted on the inner wall thereof, an alternating-current circuit and a continuous-current circuit connected to said electrodes, a body of conducting liquid, a body of insulating liquid, means tending to force liquid from both of said bodies through said tube, a valve mechanism mounted to control the 110 admission of liquid to said tube, a synchronous motor for operating said valve mechanism, and connections from said motor to said alternating-current circuit, whereby said motor operates said valve mechanism to 115 alternately admit conducting and insulating liquid to said tube. 120

5. The combination with a tube of insulating material, of a pair of spaced electrodes mounted on the inner wall thereof, an alter- 130

- nating-current circuit and a continuous-current circuit connected to said electrodes, a body of conducting liquid, a body of insulating liquid, means tending to force liquid from both of said bodies through said tube, a valve mechanism mounted to control the admission of liquid to said tube, a synchronous motor for operating said valve mechanism, and connections from said motor to said alternating-current circuit, whereby said motor operates said valve mechanism to alternately admit conducting and insulating fluid to said tube, and means for varying the relative lengths of the conducting and insulating globules admitted to said tube.
6. In a circuit-controlling device, the combination with a plurality of interconnected pairs of spaced electrodes, of means for causing a succession of moving conducting bodies to pass by said electrodes, whereby each moving body may successively complete connection between different pairs of spaced electrodes.
7. In a circuit-controlling device, the combination with means for causing each body of a succession of moving conducting bodies to successively complete connection between successive pairs of spaced electrodes, of connections between said pairs of electrodes and said circuit, whereby two of said pairs of electrodes are connected in parallel relation in the control of said circuit and two of said pairs of electrodes are connected in series relation in the control of said circuit.
8. The combination with a tube of insulating material, of a plurality of pairs of spaced conducting electrodes disposed along the inner surface of said tube, the volume of said tube between successive pairs of electrodes being substantially the same, means for passing a succession of spaced globules of conducting liquid through said tube, an alternating-current circuit having a neutral point, a continuous-current circuit having one terminal connected to said neutral point, connections from one side of said alternating-current circuit through one of said pairs of electrodes to the other terminal of said continuous-current circuit, and connections from the other side of said alternating-current circuit through another of said pairs of electrodes to said second mentioned terminal of said continuous-current circuit, and means for adjusting one of said pairs of electrodes longitudinally of said stream.
10. A circuit-controlling device comprising a tube of insulating material, a pair of spaced conducting electrodes mounted on the inner face thereof, and means for forcing a globule of conducting liquid therethrough, said electrodes being provided with tips of refractory conducting material in the direction of passage of said globule and said globule being of sufficient size to simultaneously make contact with each of said electrodes.
11. An intermittent circuit-interrupting device comprising a tube of insulating material, a pair of spaced conducting electrodes mounted on the inner face thereof, and means for forcing a succession of globules of conducting liquid therethrough, said electrodes being provided with tips of refractory conducting material in the direction of passage of said globules and said globules being of sufficient size to simultaneously make contact with each of said electrodes.
12. The combination with a mechanical rectifier, of thermo-responsive means mounted adjacent to the contact members thereof and operative to reduce sparking when energized by adjusting the time of break.
13. The combination with a mechanical rectifier, of thermo-responsive means mounted adjacent to the contact members thereof and operative to reduce the voltage across said contact members at the instant of break if sufficient voltage is present to produce sparking.
14. The combination with a source of alternating current, of a contacting, rectifying device, a unidirectional-current load having a variable back electromotive force, connections therebetween, and thermally responsive means mounted adjacent to the contact members of said rectifying device and operative to automatically adjust the time of break therebetween to the instants when the voltage of said source is substantially equal and opposite to the voltage of said load.
15. The combination with a source of alternating current, of a contacting rectifying device, a unidirectional-current load having a rising back electromotive force as current is supplied thereto, connections therebetween, and thermo-responsive means mounted adjacent to the contact members of said rectifying device and operative to advance the time of break upon the initial occurrence of sparking thereat.

16. The combination with a source of alternating current, of a contacting rectifying device, a unidirectional-current load having a rising back electromotive force as current is supplied thereto, connections therebetween, and thermo-responsive means mounted adjacent to the contact members of said rectifying device and operative to advance the time of break upon the initial occurrence of sparking thereof, and further operative to retard the time of break upon the continuance of said sparking.
17. The combination with a device subject to defective operation and having two alternative and mutually exclusive corrective adjustments which eliminate said defective operation, of two-part, automatic, corrective apparatus associated therewith, one part of said corrective apparatus being quickly operative to apply one of said corrective adjustments and the other part of said corrective apparatus being slowly operative to dominate said first mentioned part and to apply the other corrective adjustment.
18. The combination with a piece of electrical apparatus subject to sparking and having two alternative and mutually exclusive corrective adjustments which eliminate said sparking, of two-part automatic corrective apparatus associated therewith, one part of said corrective apparatus being quickly operative to apply one of said corrective adjustments and the other part of said corrective apparatus being slowly operative to dominate said first mentioned part and to apply the other corrective adjustment.
19. The combination with a piece of electrical apparatus subject to sparking and having two alternative and mutually exclusive corrective adjustments which eliminate said sparking, of two-part thermo-responsive corrective apparatus associated therewith, one part of said corrective apparatus being quickly operative to apply one of said corrective adjustments and the other part of said corrective apparatus being slowly operative to dominate said first mentioned part and to apply the other corrective adjustment.
20. The method of employing a series of moving conducting bodies, each of said bodies successively making contact with different pairs of electrodes, in the rectification of alternating current which comprises operating two pairs of said electrodes in parallel with each other.
21. The method of employing a series of moving conducting bodies, each of said bodies successively making contact with different pairs of electrodes, in the rectification of alternating current which comprises operating two pairs of said electrodes in series with each other.
22. The method of employing a series of moving conducting bodies, each of said bodies successively making contact with different pairs of electrodes, in the rectification of alternating current which comprises employing one pair of said electrodes in the rectification of alternating-current waves of one polarity and another pair of said electrodes in the rectification of alternating-current waves of the other polarity.
23. The method of controlling sparking in a mechanical rectifier which comprises placing the timing of the contact-making and breaking mechanism under the control of thermo-responsive apparatus subject to the heat generated by sparking.
24. The method of automatically correcting the operation of a device subject to undesirable operation and having two independent and mutually exclusive corrective adjustments which comprises promptly applying one of said corrective adjustments and simultaneously but more slowly applying the other of said adjustments, said slow-acting adjustment overcoming the said promptly-acting adjustment after a predetermined period.
25. The method of automatically correcting for sparking in a mechanical rectifier operating to supply a load having a variable back electromotive force which comprises automatically shifting the point of break in one direction along the alternating electromotive force wave, and, if said adjustment is ineffective, automatically shifting the point of break in the other direction along said wave.
26. The method of automatically correcting for sparking in a mechanical rectifier operating to supply a load having a rising back electromotive force which comprises first automatically advancing the time of break on each electromotive force wave of the supply, and, if said action is ineffective, subsequently automatically retarding said time of break.

In testimony whereof, I have hereunto subscribed my name this 24th day of June, 1916.

DAVID C. DAVIS.
